[57] ABSTRACT

An apparatus for the pivotable mounting of a load container at a travelling carriage or similar mechanism of overhead conveyors or the like such that the load container always is suspended vertically or perpendicularly independent of the position of the travelling carriage. The inventive apparatus embodies two support holders arranged at the load container and two swivel or hinge joint devices arranged at the suspension mechanism of the travelling carriage. Each swivel or hinge joint mechanism embodies at least two components which are rotatable relative to one another, wherein one component is fixed with the suspension mechanism of the traveling carriage and the other free component is at least partially enclosed by the associated support holder. These components of each swivel joint mechanism and the associated support holder are constructed in such a way that the suspended load container is centered with respect to the suspension mechanism in two directions which are approximately perpendicular to one another.

**APPARATUS FOR PIVOTABLY MOUNTING A LOAD
CONTAINER AT A TRAVELLING CARRIAGE OF
OVERHEAD CONVEYORS OR THE LIKE**

BACKGROUND OF THE INVENTION

The present invention relates to an improved apparatus for the pivotable mounting of a load container at a travelling carriage or similar mechanism of overhead or suspended conveyors, trolleys or the like, and specifically, in such a fashion that the load container is always hanging vertically or perpendicularly independent of the position of the travelling carriage. If load containers conveying material which require a continuous vertical or perpendicular position of the load container, for instance during the conveying of materials in open containers, are transported at overhead conveyors or trolleys, the track rails of which are not situated solely in one plane, rather are spatially arranged, i.e., possess horizontal, inclined and vertically extending track rails with suitable transfer or transition locations, then it is necessary that the mounting of the load container at the travelling carriage or the like of the suspension or overhead conveyor be constructed in such a fashion that this load container always assumes a vertical position independent of the momentary position of the travelling carriage.

One solution employed for overhead conveyors which has become known to the art contemplates suspending the load container at two hooks provided at the overhead conveyor through the agency of a respective pin member arranged at each of two sides of the load container. This solution enables the load container to always assume a vertical position. Yet, a major drawback of this type of prior art construction resides in the fact that if it is necessary for the load container to carry out movements which respect to the hooks through an angle of approximately 180°, because for instance of the arrangement of the track rail, and which can occur when transferring from a vertical rail for the upward travel of the load container to a vertical rail for the downward travel thereof, then the load container will fall from the conveying system. Not only is this dangerous for any personnel who might be in the vicinity of the system but also it results in damage to the goods being conveyed.

Apart from the foregoing significant drawbacks of this prior art solution, there is the further major disadvantage which is associated with the known support devices that it is impossible to achieve an exact lateral centering of the load container at the suspension system. This can be disadvantageous during unloading and loading of the load container. Furthermore, the suspension of the load container itself through the use of hooks is a cumbersome procedure, since these hooks must be suspended at an inclination from below at the support pins arranged at the load container.

SUMMARY OF THE INVENTION

Thus, a real need exists in the art for an improved apparatus for the pivotable mounting of a load container at a travelling carriage of overhead or suspended conveyors or the like which does not possess the aforementioned drawbacks of the prior art constructions. The present invention therefore has for one of its primary objectives to provide such an apparatus which fulfills this need.

Another, more specific object of the present invention relates to an improved apparatus for pivotably mounting a load container at a travelling carriage or the like of overhead conveyors or similar systems which affords for quick, reliable, and easy mounting and dismantling of the load container at the travelling carriage, affords adequate centering of the load container at the suspension mechanism of the traveling carriage, provides for safe transport and carrying of the loads without danger of the load container dropping off of the system when the conveying operation occurs in different positions, or requires the load container to move through different spatial directions, and finally, ensures for a conveying system which is not readily subject to breakdown and extremely capable of performing its intended function.

Now, in order to implement these and still further objects of the invention, which will become more readily apparent as the description proceeds, the inventive apparatus of the aforementioned type is generally manifested by the features that it comprises two support holders arranged at the load container and two swivel or hinge joint devices arranged at the suspension mechanism of the travelling carriage or the like. Each of the swivel joint mechanisms advantageously consists of at least two components rotatable relative to one another, one such component being fixedly connected with the suspension mechanism of the travelling carriage of the overhead conveyor and the other free component of which is at least partially surrounded or enclosed by the associated support holder. Furthermore, these components of each swivel joint mechanism and the associated support holder are constructed in such a way that the suspended load container is centered with respect to the suspension mechanism in two directions which are approximately perpendicular to one another.

BRIEF DESCRIPTION OF THE DRAWINGS

The invention will be better understood and objects other than those set forth above will become apparent when consideration is given to the following detailed description 25 thereof. Such description makes reference to the annexed drawings wherein:

FIG. 1 schematically illustrates a prior art mounting arrangement for a load container through the use of hook members;

FIG. 2 shows the prior art mounting arrangement of FIG. 1 with the hooks pivoted through an angle of approximately 90°;

FIG. 3 is a schematic representation of a preferred embodiment of inventive mounting or support apparatus for the load container of an overhead conveying system or the like;

FIG. 4 is an enlarged vertical sectional view showing details of one of the schematically depicted swivel joint devices and its associated support holder used in the mounting apparatus for a load container of a travelling carriage of overhead conveyors employed in the system of FIG. 6, and taken substantially along the line IV—IV thereof;

FIG. 5 schematically illustrates in top plan view details of the support holder used in the inventive mounting or suspension system and forming a trough, with the cover member therefor being conveniently removed for clarity in illustration;

FIG. 6 is a vertical fragmentary sectional view taken through the swivel or hinge joint mechanism and the associated trough-like support holder of FIG. 4, viewed along the line V—V thereof; and

FIG. 7 is a sectional view taken through a free disc member of a modified form of swivel or hinge joint mechanism utilizing a hydraulic dampening device.

**DETAILED DESCRIPTION OF THE PREFERRED
EMBODIMENTS**

Describing now the drawings, in FIGS. 1 and 2 there is represented a known type of mounting arrangement for load containers 1 through the use of hook members 2. The load container 1 will be seen to possess two fixed pin members 3 by means of which the load container 1 can be suspended at the hook members 2. Now, if a relative rotation occurs between the load container 1 and the hook members 2 from the position depicted in FIG. 1 to that of FIG. 2, then it will be readily apparent that with a conventional hook construction the load container 1 must fall. However, in overhead or suspension conveying systems utilizing vertical and horizontal rails, such positional changes of the suspension mechanism with respect to the load container occur, so that a hook-like suspension of the load container is not possible with such type conveying installations.

Now in FIGS. 3-6 there is depicted a preferred embodiment of inventive apparatus for the pivotal mounting of a load container at a travelling carriage or the like of suspension or overhead conveyors, trolleys or equivalent structure. Referring now specifically to FIG. 3, depicting and describing generally

the most significant elements of the system necessary to understand the construction and operation thereof, it should be understood that reference numeral 4 designates the load container equipped at two sides at its upper edge with a respective support or carrier holder 5 in the form of a trough 5a. Reference numeral 6 designates a frame portion of the partially illustrated suspended travelling carriage at which there is secured a suspension mechanism 7. Suspension mechanism 7 for the travelling carriage arrangement, generally designated by reference character 6a, will be seen to comprise a horizontally disposed support element 8 and a respective vertically depending support arm member 9 and 10 arranged at each end of this horizontally extending support element 8. Furthermore, at the free end of each support arm member 9, 10 there is arranged a respective swivel or hinge joint mechanism, designated in its entirety by reference character 50, and composed of the two components 11, 12, wherein the component 11 constitutes a pin member fixed to the suspension mechanism 7, and the other component of each swivel joint mechanism comprises a rotatable disc or plate member 12 secured to the free end of the associated pin member 11. The elements 8-12 collectively form the suspension system or mechanism 7 for the load container 4 or the like.

Continuing, it should be understood that each trough-shaped support holder 5, when the load container 4 is suspended, encircles or encompasses at least partially the associated plate or disc member 12 and bears at two locations upon such associated plate member 12, all as will be more fully explained hereinafter with respect to the discussion of the arrangement of FIGS. 4 and 5.

Now with the aid of the support holders 5 and the swivel or hinge joint devices 50, embodying the components 11 and 12 heretofore considered, it is possible to simply suspend and disconnect the load container 4 at the conveyor system. More exactly, the load container 4 is raised at the loading and unloading station to such an extent that it can travel beneath the suspension mechanism 7 without the plate members 12 contacting the associated support holders 5. Thereafter, this load container 4 is lowered onto and in contact with the plate members 12 and therefore is ready to be transported. Furthermore, one noteworthy advantage of the system heretofore disclosed and described is the fact that it is not necessary to exactly align and center the load container 4 in order to introduce the plate members 12 into the associated support holders 5. Rather, the load container 4 can be offset by a certain amount and nonetheless the swivel joint mechanisms 50 can be properly joined with the support holders 5, again as will be more fully explained hereinafter.

Now in FIGS. 4-6 inclusive, there is precisely described the cooperative relationship of each swivel joint mechanism 21, 18 with its associated support holder 19, corresponding to the support holders 5 of FIG. 3. Thus, at the support arm members 20, corresponding to the arms 9 and 10 of FIG. 3, there is secured in any suitable way a pin member 21, corresponding to pin member 11 of FIG. 3, and at which there is connected for rotation the associated plate or disc member 18, corresponding to the plate 12 of FIG. 3. Now if the load container is suspended at the travelling carriage 6a or the like, then each plate member 18 engages with the associated support holder 19. Support holder 19 is composed of a component forming a substantially roof-shaped trough 22 which is attached to the relevant sides of the load container 23 and reinforced by the wall members 24. As best seen by referring to FIG. 5, showing in plan view the roof-shaped trough 22, such is composed of four inclined walls 22', 22'' and forms a downwardly open pocket for receiving from below the associated plate member 18.

This roof-shaped configuration of each trough 22 having the mutually inclined walls 22', 22'' affords a centering of the load container, upon suspension of the load, in two directions which are perpendicular to one another. By means of the wall portions 22' there occurs a lateral centering while the inclination of the transverse wall portions 22'' ensure for a centering

in a direction which is perpendicular thereto. Consequently, the load containers 23 upon being suspended need not be exactly aligned with the suspension mechanism. It is sufficient if, upon lowering the load container 23, that the plate member

5 18 extends somewhat into the opening of each associated trough 22 of the associated support holder 19, so that the mutual position of the plate member 18 and trough 22 will automatically occur upon lowering of the load container 23. Furthermore, it will be observed that the plate member 18 10 bears at the locations 19' (FIG. 4) against the walls or wall portions 22'' of the trough 22, whereas at the apex of the trough such plate member 18 is not contacted and is freely disposed by a small amount designated by reference character 51 in FIGS. 4 and 6.

15 During operation of a suspended conveyor system or overhead conveyor, where the load container is pivotably mounted with the aid of the described swivel joint devices, it is necessary to avoid undesired oscillations or pendulations of the load container. Accordingly, it is advantageous to provide suitable dampening devices at the swivel joint mechanisms. In the arrangement of FIG. 6 there is schematically illustrated one suitable form of dampening mechanism, designated in its entirety by reference numeral 41, and constituting a spring-loaded friction brake arrangement, the spring tension of which

20 can be adjusted in suitable manner, for instance through an adjustment screw as is well known to the art. The adjustment of the friction brake 41 is advantageously undertaken when the load container is empty and can only be so strong that the empty container always again returns into the vertical or perpendicular position. In so doing, the plate member 18 should not move relative to the associated support holder 19 and the associated trough 22. This can be obtained in that the inclination of the walls 22' of the trough 22 (FIG. 5) is chosen such 25 that the braked disc or plate member 18 cannot rotate in its associated trough 22 so that the desired braking action is not relinquished.

30 A further solution for dampening device is depicted in FIG. 7 wherein a rotatable vane drive is mounted in a circular cylindrical hollow compartment of the disc or plate member of one

35 of both swivel or hinge joint mechanisms. Turning now to this embodiment of dampening device as shown in FIG. 7, it will be understood that reference numeral 30 designates one of the plate or disc members and reference numeral 31 the closed hollow compartment or space arranged inside or outside of the associated plate or disc member 30, yet fixedly connected therewith and filled with a suitable viscous liquid 32. A rotary vane member 33 is arranged within the hollow space 31, and which for instance is fixedly arranged at the rotary hinge joint pin member 11 (FIG. 3) or 21 (FIG. 6). This rotary vane member 33, together with a further web member 31a disposed at the wall of the hollow compartment 31, subdivides this hollow compartment into two chambers or regions 34, 35 communicating with one another via a channel or variable orifice 38. Channel 38 can be throttled to a greater or lesser extent through the agency of a suitable screw member 39. Further, suitable sealing means 36, 37 ensure that the dampening liquid or fluid medium 32, during relative movement of the rotary vane member 33 with respect to the housing 31, can only circulate via the bore or channel 38.

40 The rotary vane drive illustrated in FIG. 7 renders possible relative movements between the load container and the suspension mechanism greater than 180°. However, in order to ensure that upon suspension of the load containers the position of the plate members corresponds with the position of the load container, a weight 40 is advantageously arranged at the plate member 30, this weight serving to always maintain the plate member 30 in the illustrated position independent of the position of the rotary vane arrangement 33. If, for instance, a load container is suspended at a vertical conveying rail or track, then the rotary vane arrangement 33 assumes a position which is displaced by 90° from the position depicted in FIG. 7. When the load is transferred to a horizontal rail or track, then the rotary vane 33 moves back into the position of FIG. 7. Of

course, the weight 40 can be arranged in a different form, for instance, instead of radially enlarging the marginal portion of the plate member 30, as shown in FIG. 7, to axially widen same. While the weight member 40 is shown as an integral part of the associated disc or plate member 30 in the arrangement of FIG. 7, it would of course be possible to use a separate weight.

While there is shown and described present preferred embodiments of the invention, it is to be distinctly understood that the invention is not limited thereto but may be otherwise variously embodied and practiced within the scope of the following claims.

What is claimed is:

1. An apparatus for pivotably mounting a load container at a travelling carriage of an overhead conveyor or the like, such that the load container is always suspended substantially vertically independent of the position of the travelling carriage, comprising a load container having a bottom end and at least one pair of oppositely situated sides, two support holders provided for said load container at said opposite sides thereof, each of said support holders being downwardly open in the direction of the bottom end, a suspension mechanism for the travelling carriage, two swivel joint devices carried by said suspension mechanism and releasably engaging with said two downwardly open support holders, each of said swivel joint mechanisms comprising at least two relatively rotatable components, one of said components being fixedly connected with said suspension mechanism and the other freely movable component being at least partially enclosed by the associated downwardly open support holder, said components of each swivel joint device and its associated support holder having cooperating means for centering the suspended load container with respect to said suspension mechanism in two directions approximately perpendicular to one another, said cooperating means of each support holder comprises members defining a substantially roof-shaped trough open at the bottom and said cooperating means of the associated swivel joint device is defined by a substantially plate-like configured member forming said other freely movable component, said plate-like configured member being rotatable relative to the support holder, said substantially roof-shaped trough engaging said plate-like configured member nondisplaceably and without play when said load container is suspended at said swivel joint devices.

2. The apparatus defined in claim 1, wherein said plate-like configured member defining said freely movable component of each swivel joint device comprises a substantially circular-shaped plate member which is mounted at said one component connected with said suspension mechanism and which plate member can be introduced in every position into the associated support holder, said plate member bearing at two locations at said substantially roof-shaped trough and being centered thereby.

3. An apparatus for pivotably mounting a load container at a travelling carriage of an overhead conveyor or the like, such that the load container is always suspended substantially vertically independent of the position of the travelling carriage, comprising a load container, two support holders provided for said load container, a suspension mechanism for the travelling carriage, two swivel joint devices carried by said suspension mechanism and engaging with said two support holders, each

of said swivel joint mechanisms comprising at least two relatively rotatable components, one of said components being fixedly connected with said suspension mechanism and the other freely movable component being at least partially enclosed by the associated support holder, said components of each swivel joint device and its associated support holder having cooperating means for centering the suspended load container with respect to said suspension mechanism in two directions approximately perpendicular to one another, said

5 10 15 20 25 30 35 40 45 50 55 60

cooperating means of each support holder comprising at least two transverse wall members which are inclined towards one another and define a substantially roof-shaped trough.

4. The apparatus defined in claim 3, further including means for dampening movements of said load container coupled with said components of at least one of said swivel joint devices.

5. The apparatus defined in claim 4, wherein said dampening means comprises an adjustable friction brake means.

6. The apparatus defined in claim 4, wherein said dampening means comprises a hydraulic dampening device equipped with variable orifice means allowing for circulation of the hydraulic fluid medium.

7. The apparatus defined in claim 4, wherein said dampening means comprises means defining a compartment filled with a fluid medium, rotatable vane means for dividing said compartment into two chambers, and throttleable channel means for operatively coupling said two chambers with one another.

8. The apparatus defined in claim 4, wherein said dampening means incorporates a weight member for coordinating the position of said freely movable component of the associated swivel joint device with the position of the associated support holder upon suspension of the load container.

9. An apparatus for pivotably mounting a load container at a travelling carriage of an overhead conveyor or the like, such that the load container is always suspended substantially vertically independent of the position of the travelling carriage, comprising a load container, two support holders provided for said load container, a suspension mechanism for the travelling carriage two swivel joint devices carried by said suspension mechanism and engaging with said two support holders, each of said swivel joint mechanisms comprising at least two relatively rotatable components one of said components being fixedly connected with said suspension mechanism and the other

45 50 55 60

freely movable component being at least partially enclosed by the associated support holder, said components of each swivel joint device and its associated support holder having cooperating means for centering the suspended load container with respect to said suspension mechanism in two directions approximately perpendicular to one another, means for dampening movements of said load container coupled with said components of at least one of said swivel joint devices, said cooperating means of each support holder comprising inclined wall means defining a substantially roof-shaped trough, and wherein said other freely movable component comprises a plate member, the inclination of said wall means in the direction of travel of said load container being chosen to be large enough that said trough and plate member are not displaceable relative to one another under the action of said dampening means.
